(57) **CLAIM**

We claim the ornamental design for a wearable recording device, as shown and described.

DESCRIPTION

FIG. 1 is a front perspective view of the new design of a wearable recording device;

FIG. 2 is a front elevation view of the wearable recording device;

FIG. 3 is a rear elevation view of the wearable recording device;

FIG. 4 is a left side elevation view of the wearable recording device;

FIG. 5 is a right side elevation view of the wearable recording device;

FIG. 6 is a top plan view of the wearable recording device; and,

FIG. 7 is a bottom plan view of the wearable recording device. The broken lines depict portions of the wearable recording device in which the design is embodied and form no part of the claimed design.
